DOOR TRAY

Alexander Hertz, Forest Hills, N. Y.

Application June 30, 1949, Serial No. 3,641

Term of patent 7 years

(Cl. D33—3)

To all whom it may concern:

Be it known that I, Alexander Hertz, a citizen of the United States of America, and a resident of Forest Hills, in the county of Queens and State of New York, have invented a new, original, and ornamental Design for Door Tray, of which the following is a specification, reference being had to the accompanying drawing forming a part hereof, in which—

Fig. 1 is a perspective view of a door tray embodying my design.

Fig. 2 is a side elevation.

Fig. 3 is a top plan view.

Fig. 4 is an end view thereof.

I claim:

The ornamental design for a door tray, as shown.

ALEXANDER HERTZ.
